UNITED STATES PATENT OFFICE.

RALPH E. WILLIAMS, OF LOS ANGELES, CALIFORNIA.

SPOTLIGHT.

Application filed November 26, 1919. Serial No. 340,919.

To all whom it may concern:

Be it known that I, RALPH E. WILLIAMS, a citizen of the United States, residing at Los Angeles, in the county of Los Angeles, State 5 of California, have invented new and useful Improvements in Spotlights, of which the following is a specification.

The present invention relates to a spotlight and particularly to a construction for 10 attaching the reflector of a spotlight to the carrying member. It is an object of the invention to provide a simple, inexpensive, and effective construction by which the reflector of a spotlight may be attached to the 15 carrying member.

A feature of the invention is the provision of a construction or arrangement by which the reflector of a spotlight is permanently, solidly, and neatly connected to the carrying 20 member. The construction provided by the present invention is such as to cause the joint between the reflector and the carrying member to be particularly tight and solid. The joint is swedged and holds the reflector 25 so as to prevent its working loose or slipping relative to the carrying member.

There are further objects and features of the invention which will be best understood from the following detailed description of a 30 preferred embodiment of the invention throughout which reference is had to the accompanying drawings in which—

Fig. 1 is a side elevation of a lamp embodying the present invention; and Fig. 2 is 35 an enlarged vertical section of the same.

Throughout the drawings numeral 10 designates the carrying member to which is connected the reflector 11. The carrying member 10 may be of any design or construction 40 common to devices of this general character. For instance, it may be provided with a central longitudinal bore 12 and may be provided with a suitable spindle 13 by which it may be connected to or mounted on a bracket 45 of any kind.

The reflector 11 may be of any desired design or construction, the particular reflector shown in the drawings, however, being a single shell the inner surface 14 of which is 50 highly polished or finished so as to form a reflecting surface.

In the particular form of construction shown in the drawings a flange member 15 is adapted to be carried on the forward end of the mounting member 10 so as to abut 55 or engage the rear surface of the reflector

11. The flange member 15 is preferably pressed metal and forms a backing for and reinforces the reflector 11. The flange member 15 is made so as to slide freely over reduced portion 16 at the forward end of the mounting member and is adapted to engage and press against shoulder 17 formed in the mounting member as clearly shown in Figs. 2 and 4.

The reflector 11 does not necessarily connect to the flange member 15 but connects directly to the mounting member 10. The reflector 11 has a cylindrical rearwardly extending portion or neck 18 which is adapted to extend into an enlarged portion 19 of the bore 12 at the forward end of the mounting member 10. An annular recess or groove 20 is formed in the enlarged portion 19 of the bore 12 and the neck 18 of the reflector 70 is adapted to be pressed or expanded into the groove 20 as clearly shown in Figs. 2 and 4. The neck 18 of the reflector 11 is preferably expanded into the recess 20 while the mounting member 10 and the reflector 11 are being forced or pressed together. It will be readily understood that when, the neck 18 is expanded or swedged into the recess 20 while the mounting member 10 and the reflector 11 are held or forced together, the 75

mounting member 10 and the reflector 11 have a tendency to slightly move apart or separate, after the pressure is taken off of them, thereby causing the connection between the mounting member 10 and the reflector 11 to tighten. This is due to the fact that the swedged or expanded portion of the neck 18 is drawn or forced more tightly against the wall 21 of the groove 20. This form of joint between the mounting member 10 and the reflector 11 and this manner of forming or making the joint or connection have been found in practice to be particularly effective, durable and inexpensive.

It is to be understood that the construction 100 of the present invention may be made or formed in any desired manner and that the invention is not in any way limited to any method or apparatus that may be employed in its formation or assembly.

Having described a preferred embodiment of my invention I do not wish to limit myself to the specific details hereinabove set forth but wish to reserve to myself any changes or variations that may appear to 110 those skilled in the art or fall within the scope of the following claims.

Having described a preferred form of my invention, I claim:

1. In a lamp, a mounting member having a grooved bore, and a reflector attached to the mounting member, the reflector having a neck swedged into the grooved portion of the bore of the mounting member.
2. A lamp comprising a mounting member having an annularly grooved bore, and a reflector attached to the mounting member, the reflector having a neck extending into the bore and expanded into the annular groove.
3. A lamp comprising a member having a

grooved bore, a flange member carried on and backing against the mounting member, and a reflector backing against the flange member and being attached to the mounting member, the reflector having a neck extending and expanded into the grooved portion of the bore in the mounting member.

In witness that I claim the foregoing I have hereunto subscribed my name this 19th day of November, 1919.

RALPH E. WILLIAMS.

Witness:

VIRGINIA BERINGER.
